US0D1002824S

(12) **United States Design Patent** (10) **Patent No.:** **US D1,002,824 S**
(45) **Date of Patent:** **** Oct. 24, 2023**

(54) **SINK**

(71) Applicant: **BSH Hausgeräte GmbH**, Munich (DE)

(72) Inventor: **Oliver Kraemer**, Pahl (DE)

(73) Assignee: **BSH Hausgeräte GmbH**, Munich (DE)

(**) Term: **15 Years**

(21) Appl. No.: **35/514,859**

(22) Filed: **Jun. 30, 2022**

(80) **Hague Agreement Data**

Int. Filing Date: **Jun. 30, 2022**

Int. Reg. No.: **DM/222370**

Int. Reg. Date: **Jun. 30, 2022**

Int. Reg. Pub. Date: **Aug. 5, 2022**

(51) **LOC (14) Cl.** **23-01**

(52) **U.S. Cl.**

USPC **D23/284**

(58) **Field of Classification Search**

USPC **D23/284, 286**

CPC **E03C 1/04; E03C 1/18; E03C 1/186**

See application file for complete search history.

Primary Examiner — Charles D Hanson

(74) *Attorney, Agent, or Firm* — Laurence A. Greenberg; Werner H. Stemmer; Ralph E. Locher

(57) **CLAIM**

The ornamental design for a sink, as shown and described.

DESCRIPTION

3. Sink
6. Sink
9. Sink
3.1: Perspective
3.2: Perspective
3.3: Front
3.4: Right
3.5: Back
3.6: Top
3.7: Top
3.8: Left
3.9: Bottom
6.1: Perspective
6.2: Perspective
6.3: Front
6.4: Right
6.5: Back
6.6: Top
6.7: Top
6.8: Left
6.9: Bottom
9.1: Perspective
9.2: Perspective
9.3: Front
9.4: Right
9.5: Back
9.6: Top
9.7: Top
9.8: Left
9.9: Bottom

The broken line showing is included for the purpose of illustration environment and forms no part of the claimed design.

1 Claim, 27 Drawing Sheets
